CLAIM

We claim the ornamental design for a shoe outsole, as shown and described.

DESCRIPTION

FIG. 1 is a perspective view of a shoe outsole embodying the present invention shown with environment.

FIG. 2 is a front view of the shoe outsole of FIG. 1.

FIG. 3 is a rear view of the shoe outsole of FIG. 1.

FIG. 4 is a left side view of the shoe outsole of FIG. 1.

FIG. 5 is a right side view of the shoe outsole of FIG. 1; and,

FIG. 6 is a bottom view of the shoe outsole of FIG. 1.

A first embodiment of the shoe outsole is the left-foot outsole shown in the figures. A second embodiment of the shoe outsole is for the right-foot outsole, which would be a mirror image of the illustrated embodiment. The broken lines depict portions of the shoe outsole that form no part of the claimed design.
